United States Patent Office

Des. 226,079
Patented Jan. 23, 1973

226,079

GOLF CART

Paul E. Gifford, 866 Iredell St., Akron, Ohio 44310

Filed Apr. 21, 1971, Ser. No. 136,296

Term of patent 14 years

Int. Cl. D12—08

U.S. Cl. D14—3

FIG. 1

FIG. 2

Des. 226,079

PAGE 2

FIG. 4

FIG. 5

FIG. 1 is a perspective view showing my new design for a golf cart.

FIG. 2 is a top plan view thereof.

FIG. 3 is a side elevational view thereof taken from the opposite side of FIG. 1.

FIG. 4 is an end elevational view thereof taken from the front of the cart.

FIG. 5 is an end elevational view thereof taken from the rear of the cart.

I claim:

The ornamental design for a golf cart, as shown.
